ABSTRACT OF THE DISCLOSURE

The two-ladder sections of a stepladder or stool are pivotally joined at one end by top step members, one step member being pivoted to each ladder section and the two members being pivoted to each other. Spreader bars are pivotally connected to the side rails of the ladder sections and to each other, and a further link extends from the pivot joining each pair of spreader bars to the pivot joining the top step members to thus form a linkage system which controls the movements of the ladder sections both during opening and during closing of the sections relative to each other. The further link is of T-shaped cross section to present a flange to extend between the ladder sections whereby to be clamped or sandwiched therebetween when the ladder is collapsed or folded.

BACKGROUND OF THE INVENTION

In two-man stepladders or step stools, the two pivotally connected ladder sections are normally provided with spreader bars which serve to limit the spread of the ladder sections and thereby prevent them from further separation during use. When the ladder is collapsed or folded, the spreader bars serve little or no function and the ladder sections may fold off center with respect to each other and are easily subjected to racking or twisting if carelessly manipulated to folded position.

BRIEF SUMMARY OF THE INVENTION

According to the present invention, the two ladder sections are not directly pivotally connected to each other, but are, instead, pivotally joined by means of two top step members, each of which is pivotally connected to a corresponding ladder section and the two top step members being pivotally interconnected to each other. Spreader bars are provided on each side of the ladder, there being a pair of such spreader bars on each side, the spreader bars being pivotally connected at one end to their respective side rails of the ladder sections and pivotally joined together at their inner ends and a further link extends from the pivot connecting the spreader bars to the pivot connecting the top step members. When the ladder sections are spread apart, the spreader bars pivot the inner adjacent edges of the top step members downwardly so that the step members bear against the upper ends of the ladder sections and abut each other so that tread portions of the top step members lie in a common plane whereat the linkage system is locked against further spreading action.

The stated further link on each side of the ladder is provided with an inwardly directed flange or leg which lies between the ladder sections and is adapted to be clamped or sandwiched therebetween when the ladder sections are folded together.

BRIEF DESCRIPTION OF THE DRAWINGS

FIGURE 1 is a side elevational view showing a two man step stool according to this invention;

FIGURE 2 is a view similar to FIGURE 1 but showing the stool in folded or collapsed position;

2

FIGURE 3 is an enlarged perspective view partly broken away to illustrate certain details of the linkage assembly;

FIGURE 4 is a front elevational view of the step stool assembly; and

FIGURE 5 is an enlarged horizontal section taken substantially along the plane of section line 5—5 in FIGURE 4.

DETAILED DESCRIPTION OF THE INVENTION

With reference at this time more particularly to FIGURES 1 and 4, the step stool construction illustratively embodied therein includes, in general, a pair of ladder sections indicated generally by the reference characters 10 and 12 each of which comprises a pair of side rail members 14 and 16 interconnected rigidly by one or more steps such as that indicated generally by the reference character 18 in conjunction with each ladder section 10 and 12. Since the illustrative embodiment is directed to a step stool construction, it will be appreciated that only a single one of the intermediate steps 18 may be provided, although it will also be understood that for a stepladder or for a stool of greater height, additional intermediate steps 18 may be provided as desired and required.

The upper ends of the two sections 10 and 12 are pivotally interconnected by means of the top step members indicated generally by the reference characters 20 and 22, the pivotal interconnections between the respective step members 20 and 22 being effected by the pivot pin members 24 and 26 as is shown in FIGURE 1, it being appreciated that there will be a pair of such pivot pin members for each step member to pivotally connect it to its associated ladder section 10 or 12. The members 24 and 26 conveniently may take the form of rivet elements or other constructions may suitably be employed, as desired.

As may be seen better in FIGURE 3, the step members 20 and 22 may take the form of stamped plate elements provided with reinforcing and interconnecting angle elements 28 and 30 at their opposite sides. The stamping portion of each step member presents a substantially flat tread portion 32 having a downwardly angled skirt 34 on its outer side and being provided with a depending flange 36 along its inner side. The angle members 28 and 30 are attached to the undersides of the tread portions 32 at either end thereof by suitable fasteners such as those indicated by the reference characters 38 and 40 in FIGURE 3. The horizontal legs 42 of the angle members 28 and 30 are abutted directly against the undersides of the tread portions 32, substantially as is shown, with their depending leg portions 44 substantially flush with the corresponding ends of the tread portions 32 and extending downwardly to lie closely adjacent the outer sides of the respective side rails 14 of the two ladder sections 10 and 12.

The angle member 28 is provided with a straight projecting tab 48 whereas the angle member 30 is provided with an outwardly offset projection or tab 50, the two tabs 48 and 50 being overlapped as is shown and pivotally interconnected by suitable rivet or like element 52. The dimensions and arrangements of the step members 20 and 22 are such that when the ladder is in the operative position as is shown in FIGURE 3, the two tread portions 32 are substantially coplanar with the ribs or flanges 36 of the two step members being disposed in abutting relationship and with the horizontal legs 42 of the angle members 28 and 30 bearing directly against the upper ends of the respective rails 14. The pivot elements 24 and 26 which secure the step members to their respective side rails 14 are located outwardly from the pivot axis established by the elements 52 so that the step members

0 and 22 may be swung upwardly about their respective pivot axes to disengage their ribs or flanges 36 and swing the step members away from the respective upper ends of the side rails 14 substantially in the fashion as will be understood by a consideration of FIGURE 2.

A pair of spreader bars 56 and 58 are pivotally connected as by the rivets or like elements 60 and 62 to the side rails 14 on opposite sides of the two ladder sections and the inner ends of each pair of spreader bars 56 and 58 are pivotally interconnected by a suitable rivet or key element 64 and extending between the pivot member 4 and the corresponding pivot member 52 interconnecting the steps 20 and 22 is a further link 66. Thus, from a study of FIGURES 1 and 2, it will be apparent that when the parts are in the disposition shown in FIGURE 1, the linkage system is locked to prevent further spreading of the ladder sections 10 and 12 by virtue of the aforementioned bearing engagement of the top step members 0 and 22 against the upper ends of their respective side rails 14 and it will also appear that when the ladder is to be folded or collapsed, relative inward movement of the side rails 14 will cause the links 66 to be raised under the action of the spreader bars 56 and 58 to correspondingly pivot the top steps 20 and 22 upwardly at their adjacent inner edges ultimately for disposition of the component parts as is shown in FIGURE 2. It will be understood, from the above, that the linkage system includes the side rails 14 as a part thereof and is of such type as constrains all of the parts to move in definite and predetermined fashion, thus preventing the ladder sections from folding off center and assuring both a positive opening and a positive closing or folding action which obviates racking or twisting of the assembly even if the ladder is carelessly manipulated during opening and particularly closing action thereof.

To further assure stabilization of the assembly when in the collapsed or folded position, the links 66 are constructed to provide intermediate portions thereof which are of L-shaped configuration in cross section, presenting the inwardly directed flanges or legs 68 which project inwardly from the opposite sides of the ladder between the sections 10 and 12 thereof, so that when the assembly is folded, the legs 68 will be sandwiched between the corresponding side rails 14, substantially as is shown in FIGURE 5.

The present invention, therefore, is well adapted to carry out the objects and attain the ends and advantages mentioned as well as others inherent therein. While the presently illustrative embodiment of the invention is given for the purpose of disclosure, numerous changes in the details of construction and arrangement of parts may be made which will readily suggest themselves to those skilled in the art and which are encompassed within the spirit of the invention and the scope of the appended claims.

I claim:

1. A two-man ladder comprising, in combination, a pair of ladder sections each having opposite side rails and intermediate step means interconnecting said side rails, means for pivotally interconnecting said ladder sections at their upper ends, said means comprising a top step member associated with each ladder section, said top step members being pivotally connected to each other and pivotally connected to their respective ladder sections,

spreader bar means interconnecting said ladder sections below said top step members, and link means extending from said spreader bar means to said top step members for actuating said top step members directly from said ladder sections.

5 2. The ladder according to claim 1 wherein said link means is provided with a flange portion projecting between said ladder sections and adapted to be sandwiched therebetween when the ladder sections are collapsed.

10 3. The ladder construction according to claim 2 wherein in each top step member includes a flat tread portion bridging between and overlying its respective side rails, and depending flange portions at the opposite ends of said tread portion, said flange portions extending downwardly along the outer sides of their respective side rails, said flange portions having projecting tabs with the tabs of the two top step members being disposed in overlapping relation, first pivot pins connecting the overlapping tabs of said two step members, and second pivot pins connecting said flanges to their respective side rails outwardly of said first pivot pins.

15 4. The ladder according to claim 3 wherein said spreader bar means comprises a pair of spreader bars at each side of said ladder, the spreader bars of each pair being pivotally connected at their inner ends and pivotally connected at their outer ends to the respective side rails.

20 5. The ladder according to claim 4 wherein said link means comprises a link extending between the inner ends of each pair of said spreader bars and a corresponding first pivot pin.

25 6. The ladder construction according to claim 1 wherein each top step member includes a flat tread portion bridging between and overlying its respective side rails, and depending flange portions at the opposite ends of said tread portion, said flange portions extending downwardly along the outer sides of their respective side rails, said flange portions having projecting tabs with the tabs of the two top step members being disposed in overlapping relation, first pivot pins connecting the overlapping tabs of said two step members, and second pivot pins connecting said flanges to their respective side rails outwardly of said first pivot pin.

30 7. The ladder construction according to claim 6 wherein in said spreader bar means comprises a pair of spreader bars at each side of said ladder, the spreader bars of each pair being pivotally connected at their inner ends and pivotally connected at their outer ends to the respective side rails.

35 8. The ladder according to claim 7 wherein said link means comprises a link extending between the inner ends of each pair of said spreader bars and a corresponding first pivot pin.
